LEG STOOL

Percy Watt Hood and Roger Moorman,
Gloucester, Va.

Application July 2, 1948, Serial No. 147,348

Term of patent 14 years

(Cl. D15—8)

To all whom it may concern:

Be it known that we, Percy Watt Hood and Roger Moorman, citizens of the United States, residing in the city of Gloucester, county of Gloucester, and State of Virginia, have invented a new, original, and ornamental Design for Leg Stools, of which the following is a specification, reference being had to the accompanying drawing, forming part thereof, and in which

Figure 1 is a perspective view of a leg stool, showing our new design with the movable portion of the same in horizontal position;

Figure 2 is a side elevation with the movable portion of the leg stool in inclined position;

Figure 3 is a front end elevation showing the movable portion in the position illustrated in Figure 1; and

Fig. 4 is a bottom plan view of the leg stool in the position illustrated in Figure 2.

We claim:

The ornamental design for a leg stool, as shown and described.

PERCY WATT HOOD.
ROGER MOORMAN.
